METHOD AND APPARATUS FOR DISINTEGRATING RAW MATERIALS

John J. Denovan, Lachine, Quebec, and Robert A. Denovan, Sherbrooke, Quebec, Canada

Application January 2, 1951, Serial No. 204,034

8 Claims. (Cl. 241—4)

This invention relates to a method and apparatus for disintegrating raw materials and, more particularly, for removing individual fibers from masses of fibrous materials.

The invention is particularly applicable to the treatment of asbestos ore. Various types of machines are available for fiberizing such ore. A most desirable function of such machines is that the asbestos fibers be separated thereby from the natural bundles of fibers with a minimum degree of injury to the individual fibers whereby they are released in long, unbroken condition. Many attempts have been made to achieve this desirable function with some measure of success.

It is an object of this invention to provide a method and means for separating individual fibers from masses of fibrous material in a practical, convenient manner and whereby an optimum percentage of long undamaged fibers is obtained. A further object is to provide a compact, effective fiberizing machine of simple, practical construction.

The invention contemplates the provision of a gravitational flow of fibrous ore in a substantially vertical direction, the subjection of the ore during such flow to a series of impacts in each of a plurality of vertically spaced zones to loosen the coherence of the fibers in the ore, and the continuous treatment of the flow of ore with a plurality of air currents following movement through each of the zones to separate loosened fibers from the ore substantially immediately following the loosening impact, thereby preventing further damaging impacts in succeeding zones.

The invention will be described with reference to the accompanying drawings, in which

Figure 1 is a sectional elevation of a machine in accordance with the invention,

Figure 2 is an enlarged sectional plan view on line 2—2 of Figure 1,

Figure 3 is an enlarged plan view of a baffle segment,

Figure 4 is a sectional end elevation on line 4—4 of Figure 3,

Figure 5 is a front elevation of the baffle segment,

Figure 6 is an enlarged side elevation, partly in section, of a hammer mounting, and

Figure 7 is an enlarged partial plan view, partly in section, of the hammer mounting.

In the drawing, 1 is a cylindrical casing having a top closure plate 2 and a conical bottom portion 3 leading to an axial discharge outlet 4.

The casing is lined with a plurality of superimposed rings each of which is preferably of segmental character for ease of manufacture, assembly and maintenance. The bottom or lowermost ring 6 is seated upon an annular flange 5 provided at the top of conical portion 3 and comprises a plurality of segments 6', which may be bolted to the casing wall as shown. Each segment 6' carries substantially midway between its ends a radially inwardly directed finger or baffle 7, one of the lateral faces of which is radially grooved at 8 to provide a generally concave surface. Preferably, the inner surfaces of the segments are downwardly inclined, as indicated at 9, to direct downwardly the material under treatment.

Seated upon ring 6 is a second liner ring 10, the lower edge of which is preferably in interlocking engagement with the upper edge of ring 6, as shown at 11. Ring 10 is composed of a plurality of segments 10' having a serrated or saw-toothed inner surface 12.

Seated upon ring 10 and fixed to the casing is a third

2

baffle ring 13, the edge of which is in interlocking engagement with the upper edge of ring 10, as shown. Ring 13 is composed of a plurality of segments 13', the structure of which is clearly shown in Figures 3, 4 and 5. Each segment has an end wall 14 which carries a pair of vertically aligned baffles 15, which are radially inwardly disposed. One lateral face of each baffle 15 is grooved at 16 to provide a generally concave surface. By reference to Fig. 2, it will be observed that the baffles 15 are circumferentially spaced or staggered with respect to baffles 7. Each segment 13' has a rear wall 17, an inwardly extending horizontally disposed lower wall 18, and a downwardly inclined upper wall 19, the lower edge of which is spaced from the inner edge of wall 17 to provide a circumferentially extending opening 20. The rear wall 17 is open at 21 and the casing 1 has a complementary registering opening 22 to provide an air inlet or passage, the outlet of which is constituted by the opening 20. As clearly shown in Fig. 2, the openings 20 in the ring 13 provide a substantially continuous annular air outlet interrupted only by the end walls 14.

Any desired number of baffle rings 13, separated by liner rings 10, may be provided in the casing. In the embodiment illustrated, two such rings are employed, thus providing two vertically spaced annular air passages. A baffle ring 6 is provided at the top end of the casing. Each segmental ring described is shown as comprising eight segments, which has been found to be a satisfactory arrangement, but the number of segments and baffles 7 and 14 may be varied as required.

Extending axially through the casing is a stationary shaft 23, the lower end of which is supported in frame member 24, and the upper end of which is supported by a bracket 25. A tubular hub 26 is rotatably mounted on the shaft by means of a lower bearing housing 27 and an upper bearing housing 28, each fixed to the hub and having rotatable bearing engagement with the ends of the shaft. A driving sheave 29 is fixed to the upper end of the hub and to the bearing housing 28, as shown. The sheave is driven in any suitable manner (not shown).

Mounted on the hub for revolution therewith is a series of generally radially extending hammers 30, the free or outer end portions of which are arranged to revolve between the upper series of baffles 7 and the adjacent series of baffles 15. Also mounted on the hub for revolution therewith are a plurality (two as shown) series of radially extending hammers 31, the free end portions of which are arranged to revolve between the adjacent series of baffles 15 and 7. While the number of hammers in each series may vary, six has been found to be a satisfactory number.

A convenient and preferred means for mounting each series of hammers 30 and 31 on the hub comprises a plurality (four as shown) of radially extending lugs 32, and upper and lower annular plates 33 and 34, each having a respective central opening 33' or 34' of sufficient diameter to enable the plate to be passed over the lugs 32 on the hub. Each plate is provided with a plurality of complementary lugs 35 extending inwardly from the edge of openings 33' and 34'. On assembly, each pair of plates 33 and 34 are positioned with each pair of their lugs 35 in engagement with a lug 32 lying therebetween and the lugs 35 are appropriately fixed to the lugs 32 as by welding.

The inner end of each hammer 30 and 31 is pivotally secured between a respective pair of plates 33 and 34 by means of a pin 36 which extends through the inner end of the hammer and registering openings 37 and 38 in the respective plates. Plate 33 is provided with a raised portion 39 extending around each opening 37, such raised portion 39 being recessed at 40 on its inner edge to receive a laterally extending lug 41 constituting an offset head of each pin 36. The lower end of each pin 36 engages an annular flanged edge portion 42 of plate 34. The lower end of each pin is notched at 43 to receive a spring ring 44 which retains the pins in position. It will be obvious that the means for mounting the hammers, as described permits convenient removal and replacement of the hammers. Preferably, as shown, the hammers 30 are somewhat heavier than hammers 31 and their radius of revolution is somewhat shorter than that

of hammers 31. Each hammer 30 and 31 has its lateral faces grooved as indicated at 45 and 46 to provide concave impact surfaces thereon.

Closure plate 2 is provided with an axially offset ore chute 47, which as shown is located directly above the path of movement of the impact surfaces of the hammers 30.

Bottom portion 3 constitutes a discharge hopper and the outlet 4 may be connected to a cylindrical vertically disposed chute 48 forming the axial inlet passage of a concentrator 49. Chute 48 discharges onto a conical baffle 50 carried by a shaft 51 and located below and in spaced relation to the lower end of chute 48. Also carried by shaft 51 is an annular baffle 52 of frustro-conical shape and arranged below and in spaced relation to baffle 50. The outer periphery of baffle 50 preferably overlaps to a slight degree the upper periphery of baffle 52. Means for adjusting the vertical elevation of baffles 50 and 52 may be provided and, as shown, comprises a transversely extending shaft 53 connected to the lower end of the shaft through gears 54.

Located below baffle 52 is an additional baffle 55 of inverted frustro-conical shape, the upper periphery of which is fixed to the concentrator casing, as shown. It will be observed that the upper periphery of baffle 55 is of substantially greater diameter than that of the lower periphery of baffle 52, whereby material discharged from the surface of baffle 52 may be deposited upon the inner surface of baffle 55. A waste discharge chute 56 is located in the bottom wall of the concentrator. The mouth of the chute is flared as indicated at 57 to receive the discharge from the lower end of baffle 55. Moreover, the mouth of chute 56 is spaced below the lower end of baffle 55 to provide a free space therebetween.

Below baffle 56 and generally opposite the mouth portion of chute 55 is an air inlet 58 in the side wall of the concentrator. The inlet may be provided with a valve 59. An air and fiber outlet 60 is provided in the side wall of the concentrator at the upper end thereof.

Access to the upper section of casing 1 containing the hammers 30 and 31 and cooperating baffle and lining rings is preferably provided by forming the front semi-cylindrical half of this section as two doors 61 hinged at 62 to the semi-cylindrical back half of the section.

In operation, air under pressure is admitted to casing 1 through the two series of circumferential openings 20 and through opening 58 in any suitable manner (not shown). A satisfactory rate of air flow through openings 20 is 5000 cubic feet per minute, and through inlet 58, 15,000 cubic feet per minute. With the hub 26 driven to revolve the hammers 30 and 31, centrifugal force normally maintains the latter in radially extended position, but due to their pivotal mounting, they are free to swing out of such position should tramp objects, such as iron and the like, come in contact therewith. Ore is fed through chute 47 directly into the path of the upper series of hammers 30, which, since they are heavier and revolve through a smaller orbit, have a lower velocity than that of hammers 31. Thus, their impact on the pieces of ore is less intense and, to a proportional degree, their damaging effect on the first release of fibers from the ore is less. It will be observed that the series of hammers 30 (as well as each series of hammers 31) is located laterally opposite a serrated liner ring 19, which cooperates with the hammers to release fibers from the ore.

The pieces of ore, following the initial impacts of hammers 30, are subjected to an air sweeping action by the current of air flowing in through the upper circumferential openings 20 before coming into contact with the next series of hammers 31. Thus, loosened fibers are removed from the pieces of ore by the air sweeping action and the possibility of damage thereto avoided. A similar air sweeping action takes place following the succeeding application of impact blows by hammers 31.

It will be observed that the concave surfaces of the baffles 7 and 15 face in the same circumferential direction, which is opposite to the direction of revolution of the hammers 30 and 31. These surfaces are thus arranged to engage the pieces of ore following their impact with the hammers and thereby remove the rotational velocity therefrom prior to its passage through the succeeding air sweeping stage whereby more effective sweeping action is possible.

Following treatment of the ore by the lower series of

86

hammers, the released fibers and any remaining pieces of ore, as well as foreign material, are discharged through hopper 3 into the concentrator 49. The material is subjected to a relatively strong current of air in the concentrator, which, because of the arrangement of baffles and, as indicated by the arrows, is directed through the falling material at various levels during its progress through the concentrator. The air current, carrying the released fibers, emerges through outlet 60, where it is conducted to a fiber collector of usual type. It will be appreciated that the air current may be arranged in a substantially closed circuit.

Pieces of ore from which fibers have not been completely released, as well as any tramp objects in the ore, are discharged through chute 56.

There has thus been provided a simple compact fiberizing machine wherein the material under treatment flows by gravity, (1) through a fiber releasing device and (2) through an air concentrator. In the fiber releasing device, the material is subjected in successive zones to a series of impacts and immediately following treatment in each of the zones and before progress of the falling material to the next zone, the material is subjected to an air sweeping action to remove released fiber from the pieces of material.

The embodiments of the invention in which an exclusive property or privilege is claimed are defined as follows:

1. A method of fiberizing asbestos ore which comprises providing a substantially unhindered gravitational flow of said ore, applying in vertically spaced relation a plurality of series of impacts to said ore while in freely falling state in said flow to loosen fibers in said ore, and horizontally directing an air current across said flow immediately following and directly below each said application of impacts and before progress of the ore to the next said application of impacts to sweep loosened fibers from said ore.

2. A method of fiberizing asbestos ore which comprises providing a substantially unhindered perpendicular gravitational flow of said ore, applying in a plurality of vertically spaced horizontal planes a series of impacts to said ore while in freely falling state in said flow to loosen fibers in said ore, and horizontally directing an air current entirely across said flow of falling ore immediately following the application of impacts in each said plane and before progress of the ore to the application of impacts in the next said plane to sweep loosened fibers from said ore.

3. An asbestos ore fiberizing machine comprising a generally vertically disposed cylindrical casing having side and top walls, a driven cylindrical member axially mounted within the casing, and a plurality of series of substantially horizontally and radially disposed impact hammers pivotally carried by said driven member for horizontal swinging movement within the casing, the free end portions of said hammers being spaced from the opposed surfaces of said side wall to permit unrestricted gravitational flow of ore therebetween, said casing having a series of circumferentially disposed and horizontally directed air inlets located between each pair of adjacent series of impact hammers for admission into the casing of a horizontally directed air sweeping stream, the top wall of said casing having an axially offset ore feeding inlet disposed directly above the paths of said series of hammers.

4. A fiberizing machine as defined in claim 3, including means for mounting each said series of hammers on said driven member comprising an upper and a lower annular plate fixed to the driven member, the inner ends of said hammers being disposed between said plates, a pin extending through each hammer and pair of plates, means carried by the upper plate for locking the heads of said pins thereon, the lower ends of said pins each having a notch therein, and a spring ring engaging said notches to releasably retain said pins in position.

5. A fiberizing machine as defined in claim 3, including a plurality of superimposed segmental lining rings fixed to the inner wall of said casing, each alternate ring being disposed laterally opposite a respective series of hammers and having a serrated surface thereon, the remaining rings carrying radially inwardly directed baffles, the lateral surfaces of said baffles facing in one circumferential direction being concave; and said hammers having concave impact surfaces thereon.

6. A fiberizing machine as defined in claim 3, said cas-

ing having an interior side wall surface for engagement by ore thrown off by said hammers, the space between the free ends of the uppermost series of hammers and the opposing portion of said side wall surface being greater than that between the free ends of each remaining series of hammers and the opposing portion of said side wall surface, each hammer in said uppermost series being of greater weight than each hammer of the remaining series of hammers.

7. A machine for removing fibers from asbestos ore comprising a generally vertically disposed casing having a top wall and an axially offset ore feeding inlet in said top wall, a driven cylindrical member axially mounted within the casing, a plurality of series of impact hammers pivotally carried by said member for rotative movement therewith, said series of hammers being arranged in successive horizontal planes to provide a series of horizontally disposed zones of impact for said ore, said casing having a plurality of annular interior side wall surfaces of substantially equal diameter each in opposed relation to the free ends of one of said series of hammers to receive ore thrown off by said hammers, the free ends of each said series of hammers being spaced from the respective opposed side wall surface to provide unrestricted gravitational flow of ore therebetween, and means forming a plurality of circumferentially arranged and horizontally directed air inlets in said casing disposed between each adjacent pair of said impact zones to provide a zone of hori-

zontally directed air sweeping following each of said impact zones.

8. A fiberizing machine as defined in claim 7, including baffle means for reducing the rotational velocity of said ore comprising a plurality of radially inwardly directed fingers carried by said casing between each of said impact zones and adjacent air sweeping zone.
